CURL CLIP

Cecil Baker, Chicago, Ill.

Application November 1, 1946, Serial No. 707,258

1 Claim. (Cl. 132—46)

1

This invention pertains to pins used in the styling of hair. More particularly it refers to hair pins or clips used by hairdressers in beauty salons, at home and wherever a need for this improved type of pin arises.

In setting up a hairdo for milady, the artiste skillfully gathers wisps of hair into an attractive arrangement and work of manipulative art. It is then necessary to set or fix it in that position by means of some unnoticeable or transparent mucilaginous material of a gummy or adhesive nature. While the hairdo is still moist, the mucilaginous substance has little strength. Various means are utilized to retain the configurations of the coiffure as set by the artiste until the hair is dry and ready for the next operation.

To accomplish this result, high speed hair dryers, a great quantity of hairpins and an innumerable variety of various clips are used and required to do an attractively set coiffure. The hairpins most generally used are known as "bobby pins" which consist of a flat metallic member of a spring-like nature folded over itself. One of the folded legs is undulated, while the other generally is flat. Both legs lie in close, parallel and flat contacting relationship because of the inherent spring characteristics set in the metal. In order to use this type of a pin in setting a hairdo—and there are literally more than a hundred used in each coiffure arrangement—the hairdo artiste must open each pin individually and place it about the strands or wisps of hair that have been temporarily curled on a convenient finger. To obtain a flat and evenly contoured appearance of each little curllet, several pins are criss crossed or interlocked and set thru the ringlet until the hair strand reaches the requisite degree of neatness. Of course, this operation is repeated about the head of milady until the desired final contemplated appearance is achieved. The subject's hair is gently treated with warm air until the adhesive is set and the hair is dry. When dry, the coiffure artiste removes all of the pins. Since there are very many pins, some use a magnet to attract the pins and pull them out of the interlocking relationship. Others again use fingers to extract the pins. But regardless of the method used, most of them remove the pins without opening the pins. This operation is faster but does not give the patron the desired appearance for the hair is mussed up to some extent. It is claimed by some that this is a desired effect, for it softens the hard lines, but to a master it behooves and indicates careless technique, for a hairdo should be a masterpiece of perfection.

2

It, therefore, is an objective of this invention to provide a means that can be readily used to assist the master to obtain a masterpiece of coiffure arrangement.

5 It is a further object of this invention to provide a means that will replace very many of the pins used in setting a hairdo.

A still further object of my invention is to decrease the number of operations required in setting hair, overcome the tediousness of opening and inserting large numbers of pins into position and otherwise improve the technique of hair setting.

15 An additional object of my invention is to provide a means that can be readily made at low cost and which particularly one skilled in the art of hair dressing can readily perceive.

These and other objects, variations, modifications and extensions will be seen, made and improvised by anyone skilled in this art when the clear and detailed description given hereinbelow is carefully studied particularly in view of the hereto appended drawing which is a part of this specification and within the purview of the 25 claim in this application.

Figure 1 is a plan view of one type of a spring element.

Figure 2 is a side view of a pivot pin.

Figure 3 is a plan or top view of the lower part 30 of the clip, while Figure 4 is a similar view of the upper part of the clip. Figures 5 and 6 show the respective side views corresponding to the elements shown in Figures 3 and 4.

Figure 7 is a side view of the assembled hairdo 35 clip ready for use.

In its preferred form, the hair clip consists essentially of four members or elements. The bottom piece 10 is a flat member of a particular configuration. In the upper portion of the said flat element 10, is a circular space 12 cut into the member 10 to provide a convenient non-slipping space rest for the adhesively covered fingers of the beauty operator. A somewhat similarly shaped space 14 is also provided in the upper member 20. When the flat members 10 and 20 are in their assembled position, the space 14 is congruently superimposed over the lower positioned space 12. Thus in the assembled hairdo clip, a convenient and definite provision is made to prevent the hair clip from slipping from the adhesively coated, slippery fingers of the hair operator.

The lower end 16 of the bottom flat element 10 is provided with an arrow or spear point, while the lower end 18 of the upper flat member 20, is provided with a somewhat similarly shaped

point 22, which points when assembled as shown in Figure 7 coincide and meet at their extremity. A large space resembling a bullet image 24 is substantially bounded by the narrow perimeter 26, which begins at about the spear point 16, and terminates in a semicircular form substantially below the circular space 12. In the upper flat member 20, there is provided a somewhat similarly shaped space 40, except that it is constricted about its midpoint 36 to a width that will fit within a portion of the space 24 bounded by the perimeter 26. This condition is achieved when the flat member 20 is angularly bent substantially as shown in Figure 6.

Extensions or lugs 28, 30, 32 and 34 are provided respectively in the flat members 10 and 20. These lugs are bent at right angles to the face of the flat members 10 and 20 to face each other. Holes 36' and 38 (and others not shown) are provided in the lugs to act as bearings for a pivot pin 41. The latter after insertion in position in the bearings, locks the entire assembly when it is bent substantially as shown in Figure 2.

A helical spring element 42 with outstanding prongs 44 and 46 is mounted on the pin 41 between the lugs 28, 30, 32 and 34. Obviously other types of spring element may be used to obtain the desired result of closing the assembly.

The assembly is produced by inserting B into the cavity of A and inserting the pin C thru the holes in the upstanding lugs and through the spring D which is mounted on the pin as a shaft.

In operation, a curlet of hair is twisted or formed on the operator's finger which has been dipped in an adhesive. However, a majority of operators prefer to moisten the hair with the adhesive and then form it into a ringlet or chord about their finger. When the ringlet is formed, a clip is opened by pressing the upper ends. The ringlet is inserted between the open jaws of the clip. The hair is held in place but is not pinched flat for there is a certain amount of space between the jaws to permit slight expansion of the chord of hair. The central portion of the ringlet is a void and into this void is positioned the angular protuberance 48. When the pressure is released the ringlet is firmly confined in place but

not pressed into a flat shape. When the hair is dry the clip is removed and the hairdo is practically finished, since very little additional work is needed. In most cases only one clip is needed and if necessary two can be employed to form one ringlet. Thus, it is obvious that a saving in time and labor is accomplished when my improved hairdo clip is used.

Having described my invention, it is obvious that one can vary greatly many of the details as shown in the above example or illustrated in the attached drawing and therefore it is my intention to be limited specifically to those fundamental concepts as defined herein in the appended claim:

I claim:

A hairdo clip adapted for the formation of soft, rounded ringlets comprising two spear-like, flat members, a prong-like projection within the spear portion of one of said flat members, a recess within the spear-like section of the other flat member to receive said prong-like projection, a means to maintain said flat members in contacting juxtaposition, a free space formed about said projection when said flat members are in contacting juxtaposition to confine but not press a hair ringlet set within said space, and finger receiving recesses in the wider portions of said flat members whereby the operator can readily manipulate the clip.

CECIL BAKER.
